AIR FLOW MEASURING DEVICE

Howard V. Nielsen, 5119 W. 22nd Place, Cicero, Ill.

Filed Aug. 16, 1965, Ser. No. 86,603

Term of patent 14 years

(Cl. D52—6)

FIGURE 1 is a front elevational view of an air flow measuring device embodying my new design;

FIGURE 2 is a side elevational view of one side of the air flow measuring device embodying my new design, the other side being a mirror image thereof;

FIGURE 3 is a rear elevational view thereof;

FIGURE 4 is a top plan view thereof; and

FIGURE 5 is a bottom plan view thereof.

I claim:

The ornamental design for an air flow measuring device, as shown and described.
